UNITED STATES PATENT OFFICE.

EDGAR B. KERST, OF PROVIDENCE, RHODE ISLAND, AND HERMAN BOGATY, OF PHILADELPHIA, PENNSYLVANIA, ASSIGNORS TO THE PHILADELPHIA TEXTILE MACHINERY COMPANY, OF PHILADELPHIA, PENNSYLVANIA, A CORPORATION OF PENNSYLVANIA.

CONVEYER.

1,288,427.

Specification of Letters Patent. Patented Dec. 17, 1918.

Application filed March 11, 1918. Serial No. 221,824.

To all whom it may concern:

Be it known that we, EDGAR B. KERST, a citizen of the United States, and a resident of Providence, Rhode Island, and HERMAN BOGATY, a citizen of Russia, (having declared his intention of becoming a citizen of the United States,) and a resident of Philadelphia, Pennsylvania, have invented certain Improvements in Conveyers, of which the following is a specification.

Our invention relates to certain improvements in conveyers used particularly in carrying material to be dried through drying machines and also relates particularly to that type of conveyer consisting of a series of comparatively long links connected together by transverse pivot pins which support the carrying apron, which is generally made of wire or some perforate material.

The object of the present invention is to provide the links with guards which extend over and under the edges of the carrying apron so as not only to protect the selvage edge where a wire frame is used, but also to support the apron when comparatively heavy weights are being carried and to prevent material from being blown off of one side of the apron during its passage through the conveyer.

In the accompanying drawings:

Figure 1 is a plan view of a portion of our improved conveyer;

Fig. 2 is a longitudinal sectional view on the line 2—2, Fig. 1, showing the conveyers passing over a portion of the sprocket wheel;

Fig. 3 is a transverse sectional view on the line 3—3, Fig. 1;

Fig. 4 is a detached perspective view of one of the links;

Fig. 5 is a detached perspective view of the two guard plates;

Fig. 6 is a plan view of a portion of the conveyer, illustrating a modification of the invention;

Fig. 7 is a transverse sectional view on the line 7—7, Fig. 6;

Fig. 8 is a detached perspective view of one of the links, showing the integral guards; and

Fig. 9 is a view of a modification. 55 5 is the conveyer, in the present instance, having links 2 and 3 of wrought metal arranged in pairs, one set of links alternating with another set on the pivot rods 11, which extend the full width of the conveyer. Between the links 2 and 3 at each side of the conveyer are the supporting wheels 4, which revolve loosely on bushings carried by the 60 links. This is an ordinary form of conveyer chain.

5 is the carrying apron, which extends from one pivot rod 11 to another and, in the present instance, is made of longitudinal and transverse wires forming a comparatively coarse mesh screen. The longitudinal wires of one apron alternate with those of another apron on the same shaft and as the screen is substantially the same length 70 as the links, it passes freely around the sprocket wheel 6 with the links. These aprons are usually made with a selvage at each edge and as the conveyer travels through the drying chamber, for instance, 75 the selvage edge is liable to rub and wear, if not protected, and, furthermore the weight of the material causes the aprons to sag between their supports. We provide the upper guard 7, which extends over the 80 edge of the apron and the lower guard 8, which extends under the edge of the apron, as clearly shown in Fig. 3. These guards are made as shown in Fig. 5 and are spot welded or otherwise secured to the inner 85 link 3. The guards are shorter than the links so as to give the conveyer perfect freedom at the pivot points. The lower guard 8 acts as a support for the edges of the apron between the pivot rods, preventing 90 the sagging of the apron to such an extent as not to interfere with the proper handling of the material, while the upper guard 7 not only protects the selvage edge, but also prevents material from escaping laterally from 95 the apron as it passes through the drying chamber and also prevents the rubbing of the apron against the stationary guard plates 9 located above the edges of the 100 aprons, as shown in Fig. 3.

The conveyer, in the present instance, travels on angle rails 10. The horizontal

portion of the angle rail supports the rods while the vertical portion limits the lateral movement of the conveyer.

In the above description, we have referred

- 5 to the guards and links as made of sheet metal and the guards secured to the links by spot welding, or other fastening devices. In some instances, however, the guards may form an integral part of the link 3^a, as
- 10 shown in Fig. 9, in which the sheet metal plate is bent to form two guards 7^a and 8^a.

In Figs. 6, 7 and 8, we have shown our invention as applied to a conveyer in which the links 2^b and 3^b are made of malleable iron and the guards 7^b and 8^b are cast integral with the links.

We claim:

1. The combination in a conveyer, of side links connected together by transverse pivot rods to form an open center chain; a series 20 of aprons mounted on the rods and of substantially the same length as the links, but free of the links; and upper and lower guards on the links projecting laterally

therefrom, one set of guards extending over 25 the edges of the aprons and the other set of guards extending under the edges of the aprons.

2. The combination in a conveyer, of two sets of links, one set being on one side of the 30 conveyer and the other set being on the opposite side; transverse pivot rods connecting the sets of links; aprons made of transverse and longitudinal wires, the longitudinal wires engaging the pivot rods; upper and lower 35 guards secured to the links at each side, one set of guards extending above the edge of the aprons and the other set of guards extending below the edge of the aprons; and stationary guard plates located above the 40 edges of the aprons and extending to a point close to the upper guards of the links so as to prevent air currents blowing material from the aprons, the lower guard preventing the aprons from sagging.

In witness whereof we affix our signatures.

EDGAR B. KERST.
HERMAN BOGATY.
